UNITED STATES PATENT OFFICE.

WILLIAM P. BROWN, OF LONDON, ONTARIO, CANADA.

FURNACE.

1,201,250.

Specification of Letters Patent. Patented Oct. 17, 1916.

Application filed January 25, 1915. Serial No. 4,223.

To all whom it may concern:

Be it known that I, WILLIAM P. BROWN, a citizen of the Dominion of Canada, residing at the city of London, in the Province of 5 Ontario and Dominion of Canada, have invented certain new and useful Improvements in Furnaces, of which the following is a full, clear, and exact description.

This invention relates to improvements in 10 furnaces, of all descriptions, and the object is to provide means for burning certain of the products of combustion which usually escape in the form of flue gases.

A further object is to provide means for 15 supplying additional oxygen to the fire for the purpose of preventing in some measure the escape of combustible gases to a region beyond the fire.

It is well known that in the combustion of 20 fuel, the two principal gases formed are carbon monoxid and carbon dioxid, the former of which is readily combinable with oxygen, that is to say, combustible, while the latter is not combinable with oxygen and is therefore 25 incombustible, and furthermore, cannot by any ordinary means be decomposed to yield a combustible gas. The monoxid is a lighter gas than the dioxid, and therefore readily separates from the dioxid.

30 With these facts in mind, the device forming the subject of this invention has been produced, and comprises essentially means for separating the carbon monoxid and carbon dioxid in a furnace and collecting the monoxid, which is then discharged with 35 sufficient oxygen for combustion into the zone of incandescent gases immediately above the fire, so that combination of the monoxid and oxygen takes place with an 40 evolution of heat. The same means may be proportioned to discharge into the fire considerable oxygen in excess of that required to consume the collected monoxid, so that 45 combustion of the fuel is carried on more perfectly than usual and the production of carbon monoxid in a measure prevented.

In the drawings which illustrate the invention, and show its application to a hot air furnace:—Figure 1 is a vertical sectional view. Fig. 2 is a plan view with the casing in section.

50 Before proceeding with the detailed description of this particular application, it must be pointed out that the hot air furnace has been selected for illustration for the reason, firstly, that it is very well known,

and secondly, that its construction is such that the invention may be applied without changes to the furnace itself, such as would be necessary with many other types of furnace. It must, however, be understood that the invention is in no way limited to this particular type of furnace, as it may be applied equally well to practically all other types, when the necessary changes, which 60 cannot all be contemplated in advance, have been made in the furnace structure.

Referring more particularly to the drawings, 11 designates a fire pot in which the fuel is placed for combustion, 12 a dome or 65 combustion chamber above the fire pot, having its top 13 concave on the surface adjacent the fire. The combustion chamber or dome 12 is surrounded by an annular radiator 14, into which the products of combustion 70 from the dome discharge through flues 15. A direct draft flue 16 is provided leading from the dome, and an indirect draft flue 17 is provided leading from the radiator into the direct draft flue, on the opposite side of a damper 18 from the dome. The indirect draft flue has a separate 75 damper 19. The whole structure is surrounded by a casing 20 within which air is circulated to be heated. This structure is 80 all well known and has been selected as an illustration of the application of the present invention, for the reason that the ample combustion chamber forms an admirable means for separating carbon monoxid and 85 carbon dioxid, when combined with the indirect draft, ordinarily maintained through the radiator. Other types of furnaces do not possess a large unobstructed chamber 90 for the separation of gases, and are all, with the exception of the cook stove, of direct 95 draft construction. It will, therefore, be seen that to illustrate the application of this invention to such furnaces, would entail description and illustration of numerous furnace modifications, which are really irrelevant 100 to the present matter.

A manifold 21 is provided leading from the highest point of the dome 12, and serving for the connection of a plurality of 105 pipes 22 which extend a suitable distance down the side wall of the dome externally thereof. A suitable length of the lower ends of each pipe 22 is incased in a larger pipe 23, the lower end of which discharges into 110 the bottom of the dome or top of the fire pot, according to the construction of the furnace.

The upper end of the pipe 23 is provided with a branch 24, which leads directly to the open air, being provided with a strainer or grate 25 to prevent the entrance of foreign objects. It will be noted in the drawings, and is an essential feature, that the pipe 24 or continuation of the pipe 23 be so formed that gases will flow through the pipe 23 in the same direction as gases issuing at the mouth of the pipe 22.

The operation of the device is in substance as follows:—The dome 12 forms a gas receiver in which the light carbon monoxid stratifies above the heavier carbon dioxid. The monoxid is thus collected and is drawn off through the manifold 21 and pipes 22, while the incombustible dioxid normally passes through the flues 15 into the radiator 14, so that the greatest possible amount of heat may be extracted from the same before it is permitted to escape from the furnace. The uprush of gas from the fire past the mouths of the pipes 23 creates a certain induced draft in these pipes, which draws air down through the pipes into the zone of combustion. This flow of air draws the carbon monoxid down through the pipes 22 to mingle with the air in the pipes 23 and be discharged into the zone of combustion. The flow of monoxid is of course assisted by the upward pressure of gases rising from the fire. It will thus be seen that the carbon monoxid is returned with sufficient oxygen for its combustion into the zone of combustion, where it combines with the oxygen producing an evolution of considerable heat. The air flues 23 are preferably proportioned to carry considerably more oxygen than is required for the combustion of the monoxid, so that as much as possible of the monoxid

produced in the fire for lack of sufficient oxygen will be consumed before leaving the zone immediately above the fire. Furthermore, this additional supply of oxygen will provide for the more perfect combustion of the fuel itself, by combining with the minute particles of carbon which are usually carried off in an atmosphere of carbon dioxid, and give to the same the characteristic colors of smoke.

Having thus described my invention, what I claim is:—

1. In a furnace, a gas collector, a main flue leading therefrom, a radiator, a connection between said radiator and said flue, means for separating the lighter combustible gases from the heavier incombustible gases comprising pipes for conducting the heavier incombustible gases into said radiator and air receiving conduits for returning the lighter combustible gases to the zone of combustion.

2. In a furnace having a fire box, a gas collector, a main flue leading therefrom below the top of said collector, a radiator, a connection between said radiator and said flue, means for separating the lighter combustible gases from the heavier incombustible gases comprising pipes for conducting the heavier incombustible gases into said radiator and air receiving conduits connecting the top of said collector with said fire box for returning the lighter combustible gases to the zone of combustion.

In witness whereof, I have hereunto set my hand in the presence of two witnesses.

WILLIAM P. BROWN.
